[57] CLAIM

The ornamental design for a gemstone mounting, as shown and described.

DESCRIPTION

FIG. 1 is a top plan view of a gemstone mounting showing our new design;

FIG. 2 is a right side elevation view thereof. The gemstones are shown in broken lines for illustrative purposes only and forms no part of the claimed;

FIG. 3 is a bottom elevation view thereof;

FIG. 4 is a left side elevation view thereof;

FIG. 5 is a front side elevation view thereof; and

FIG. 6 is a rear elevation thereof.

FIG. 7 is a top plan view of a gemstone mounting showing the similar design without having prongs. The gemstone is shown in broken lines for illustrative purposes only and forms no part of the claimed;

FIG. 8 is a right side elevation view thereof;

FIG. 9 is a bottom elevation view thereof;

FIG. 10 is a left side elevation view thereof;

FIG. 11 is a front side elevation view thereof; and,

FIG. 12 is a rear elevation thereof.
